[57] CLAIM

[**] Term: **14 Years**

The ornamental design for a rectangular-shaped heat container for heat resistant materials, as shown and described.

[21] Appl. No.: **29/073,146**

DESCRIPTION

[22] Filed: **Jul. 1, 1997**

FIG. 1 is a perspective view of the rectangular-shaped heat container for heat resistant materials;

[30] Foreign Application Priority Data

FIG. 2 is a side view of the rectangular-shaped heat container for heat resistant materials, the opposite side being mirror image thereof;

Jun. 10, 1997 [IT] Italy BS9700014

FIG. 3 is a top view of the rectangular-shaped heat container for heat resistant materials;

[51] LOC (6) Cl. **07-01**

FIG. 4 is a bottom view of the rectangular-shaped heat container for heat resistant materials; and,

[52] U.S. Cl. **D7/605**

FIG. 5 is an end view of the rectangular-shaped heat container for heat resistant materials, the opposite side being mirror image thereof.
